UNITED STATES PATENT OFFICE.

CHARLES R. HARRIS AND RUTHERFORD G. GOLDMAN, OF LOS ANGELES, CALIFORNIA.

ROTARY FLUID-BRAKE.

1,127,237.

Specification of Letters Patent.

Patented Feb. 2, 1915.

Application filed September 28, 1911, Serial No. 631,847. Renewed July 1, 1914. Serial No. 848,481.

To all whom it may concern:

Be it known that we, CHARLES R. HARRIS and RUTHERFORD G. GOLDMAN, citizens of the United States, residing at Los Angeles, in county of Los Angeles and State of California, have invented certain new and useful Improvements in Rotary Fluid-Brakes, of which the following is a specification.

Our invention relates to an improvement 10 in brakes, and the object is to provide suitable valve mechanism for controlling the compression of the fluid in the brake cylinder or casing, for controlling the speed of the vehicle or car to which it is applied. 15 When the valves are open there will be no compression in the cylinder, but as soon as the valves are closed or partially closed the fluid is compressed and the vehicle is either stopped or the speed is lessened. 20 The invention consists of certain novel features of construction and combinations of parts which will be hereinafter described and pointed out in the claims.

In the accompanying drawings, Figure 1 25 is a view in side elevation, with a portion of the casing broken away to show the interior construction; Fig. 2 is a horizontal sectional view; Fig. 3 is a view in elevation, with the outer side plate removed, and a 30 portion of the parts broken away to disclose the interior construction; Fig. 4 is a view partly in end elevation, and partly in vertical section; and Fig. 5 is an end view of one of the cylinder heads.

35 A represents the brake cylinder or casing, which is provided with side plates 1 and 2. The cylinder and side plates are connected together by means of bolts 3, 3. Interposed between the cylinder and side plate 1 are disks 4 and 5, which disks are held in position by the bolts 3.

40 A shaft 6 is journaled in the side plates 1 and 2 in suitable bearings, and keyed to the shaft is a runner or large gear wheel 7, which is adapted to mesh with pinions or cylinder heads 8, 8, which are mounted on shafts 9 journaled in the side plates. Three roller-pistons or compressor heads 10, 10 are mounted in the casing, and received in recesses 11, formed in runner. The pistons are carried by the runner during its rotation for compressing the air or fluid which is between the cylinder and runner and cylinder heads. The cylinder heads 8 are each provided with a recess 12 in which the pistons

enter to permit the pistons to pass the heads during the rotation of the runner.

The side plate 1 is provided with recesses forming equalizing chambers 13, 13 in which the air or fluid passes from the cylinder 60 through the ports 14, 14 in the disk 5, and orifices or ports 15 in the disk 4. The ports 14 are located on each side of the cylinder heads, so that as the fluid is compressed in the cylinder between the cylinder heads and 65 pistons the fluid can pass out of the path of the pistons through the ports into the equalizing chamber and thence into the cylinder on the opposite side of the heads through the ports on the opposite side of the heads. 70 The approach of the pistons toward the heads causes the fluid to pass into the equalizing chambers, and as the pistons pass the heads the suction created by the pistons 75 draws the fluid from the equalizing chambers.

An annular recess or groove 16 is formed in the runner 7, and received in the groove are dogs 17, 17. These dogs are pivotally connected to the disk 5, and the free ends of 80 the dogs are connected together by a helical spring for normally holding them out of engagement with the inner surface of the rim of the runner. The inner surface of the rim of the runner and the outer surface of 85 the dogs is made, preferably, undulating or wavy, so that when the dogs are brought into engagement with the runner an engagement will be formed whereby the dogs 90 and runner will be locked together, and the runner prevented from rotating.

Slide valves 18, 18 are mounted in recesses in the disk 5, and are adapted to be shifted or moved for closing and opening the ports 14 and 15 in the disks 5 and 4, respectively. 95 This is accomplished by a crank shaft 19 journaled in the plate 1, to which is connected a yoke 20 by a link 21. Connected to each end of the yoke is a bell crank 22, which bell cranks are pivotally connected 100 to the disk 4. Pins 23, 23 connected to the valves 18 pass through slots 24 in the disk 4 and are connected to the bell-cranks, whereby upon the rotation of the crank shaft 19 the valves are caused to move for either closing or opening the ports in the disks 4 and 5. Slots 25 are formed in the disk 5 through which pins or studs 26 connected to the dogs 17 extend. These studs 26 extend through elongated slots 27 formed 110

in the valves 18 whereby the dogs are brought into engagement with the rim of the runner when the valves close the ports, as the rear wall of the slots will engage the pins or studs causing them to be carried with the valves thereby bringing them in engagement with the runner. The closing of the ports causes a compression of the fluid in brake cylinder thereby exerting a resistance on runner preventing it from rotating at the speed when the ports are open, and by causing the dogs to be brought into engagement with the runner, the runner will be stopped and therefore the car or vehicle will be brought to a stop. The amount of resisting or braking force exerted upon the runner depends upon the extent the ports in disk 5 are closed by the valves. The valves will not carry the dogs into engagement with the runner until they are moved to their limit of movement in closing the ports.

It will be noted that the cylinder is divided into two compression chambers, and that compression takes place between two of the pistons and the two cylinder heads at all times.

The shaft 6 represents the axle or drive shaft, and therefore when the axle of a car rotates the runner 7 will rotate. The rotation of the runner causes the cylinder heads to rotate due to the engagement of the teeth of the runner with the teeth of the heads, and the pistons will be carried with the runner and cause the air to be compressed between the heads and pistons. If the valves are wide open the air or fluid will pass through the ports and thence into the cylinder on the opposite side of the heads from that in which the compression is taking place, and therefore the runner will travel freely, but as soon as the ports are partly closed by the valves 18 the free circulating of the fluid is interfered with, and a resistance is exerted on the runner reducing its speed thereby reducing the speed of the car, by the compression before and the suction behind the piston heads. Of course, when the valves are entirely closed the compression is such that the travel of the runner will be impeded to such an extent that it will be caused to stop, and when the valves are thrown to their limit of movement the dogs are actuated causing them to engage the runner and thereby assisting in bringing the runner and car to a stop.

From the foregoing it will be seen that a device has been provided which will be positive and uniform in its action; frictionless and free from the wear and tear caused by wornout brake shoes and bands.

It is evident that many slight alterations might be made in the form and arrangement of the various parts without departing from the spirit and scope of our invention,

and hence we do not wish to be limited to the exact construction herein set forth.

Having fully described our invention, what we desire to secure by Letters Patent is:—

1. In a rotary fluid brake, the combination with a casing and a runner having a compression chamber formed therebetween, of cylinder heads mounted on the casing and pistons mounted on the runner for compressing the fluid in the compression chamber, equalizing chambers in communication with the compression chamber for conducting the fluid from the high pressure to the low pressure sides of the cylinder heads and means for controlling the flow of the fluid through said equalizing chambers. 70

2. In a rotary fluid brake the combination with a casing and a runner having a compression chamber formed therebetween, of a cylinder head mounted in the casing and a piston mounted on the runner for compressing the fluid in the compression chamber between the head and piston, an equalizing chamber in communication with the compression chamber for conducting the fluid from the high pressure to the low pressure side of the cylinder head, and means for controlling the flow of the fluid through said equalizing chamber. 80

3. In a rotary fluid brake, the combination with a casing and a runner, one of which is stationary, having a compression chamber formed therebetween, of cylinder heads mounted on the casing and pistons mounted on the runner for compressing the fluid in the compression chamber, equalizing chambers in communication with the compression chamber for conducting the fluid from the high pressure to the low pressure sides of the cylinder heads and means for controlling the flow of the fluid through said equalizing chambers. 90

4. In a rotary fluid brake the combination with a casing and a runner, of cylinder heads mounted in the casing and pistons on the runner for forming at least one compression chamber for each cylinder head, said heads and pistons compressing the fluid in the chambers, equalizing chambers in communication with the compression chambers for conducting the fluid from the high pressure to the low pressure sides of the cylinder heads and means for controlling the flow of the fluid through said equalizing chambers. 100

5. In a rotary fluid brake, the combination with a casing and a runner, having a chamber formed therebetween, of cylinder heads mounted in the casing and roller pistons loosely mounted in the runner, dividing the chamber into two compression chambers, equalizing chambers for conducting the fluid to the chambers, said pistons compressing the fluid in the chambers and fore- 110

ing it through the equalizing chambers and drawing it from the equalizing chambers into the compression chambers, said cylinder heads having recesses therein whereby 5 the pistons are capable of passing the heads as they rotate through the casing, and means for controlling the flow of fluid through the equalizing chambers.

6. In a rotary fluid brake, the combination with a casing and a runner, of cylinder heads in the casing and pistons on the runner for compressing the fluid in the casing, means for conducting the fluid from and into the path of the pistons, means for 15 controlling the flow of the fluid, and means connected to said controlling means adapted to engage the runner when the controlling means is moved to its limit of movement for assisting in stopping the runner.

20 7. In a rotary fluid brake, the combination with a casing and a runner, of cylinder heads in the casing and pistons on the runner for compressing the fluid in the casing, means for conducting the fluid from 25 and into the path of the pistons, means for controlling the flow of the fluid, and dogs connected to the controlling means adapted to engage the runner for assisting the stopping of the runner when the controlling 30 means shuts off the flow of the fluid.

8. In a rotary fluid brake the combination with a casing and a runner having a compression chamber formed therebetween, of cylinder heads mounted on the casing, 35 pistons mounted on the runner dividing the compression chamber into a plurality of compression chambers, equalizing chambers in communication with the compression chamber for conducting the fluid from the high pressure to the low pressure sides of the cylinder heads, and means for simultaneously controlling the flow of fluid from the high pressure to the low pressure side of all of the cylinder heads.

40 45 9. In a rotary fluid brake, the combination with a casing and a runner having a compression chamber formed therebetween, of cylinder heads mounted in the casing and pistons on the runner, equalizing cham-

bers in communication with the compression chamber for conducting the fluid from the high pressure to the low pressure sides of the cylinder heads, and means for simultaneously controlling the flow of the fluid through the inlet and outlet of the equalizing chambers.

10. In a rotary fluid brake, the combination with a casing and a runner, of cylinder heads mounted in the casing and pistons on the runner, equalizing chambers for conducting the fluid from the high to the low pressure side of the cylinder head, said chamber having ports communicating with the high and low pressure sides of the cylinder heads, and means for controlling the flow of the fluid through said equalizing chambers.

11. In a rotary fluid brake, the combination with a casing and a runner, of cylinder heads in the casing and pistons on the runner for compressing the fluid in the casing, means for controlling the flow of the fluid and means connected to said controlling means adapted to engage the runner when the controlling means is moved to its limit 75 of movement for assisting and stopping the runner.

12. In a rotary fluid brake, the combination with a casing, of a runner, of cylinder heads in the casing and pistons on the runner for compressing the fluid in the casing, 80 passages for conducting the fluid from the high pressure to the low pressure side of the cylinder heads, means for controlling the flow of the fluid through the passages, and 85 means connected to said controlling means adapted to engage the runner when the controlling means is moved to its limit of movement for assisting and stopping the runner.

In testimony whereof we affix our signatures, in the presence of witnesses.
